CABINET CONSTRUCTION

Donald B. Keim, Bridgeport, Conn., assignor to
 General Electric Company, a corporation of
 New York

Application October 21, 1946, Serial No. 704,670

1 Claim. (Cl. 312—323)

1

My invention relates to a cabinet construction for high frequency apparatus and, in particular, to the construction of a cabinet for apparatus requiring considerable servicing.

It has been found, in the use of high frequency apparatus of the type employed for the location of objects by radio waves, that it is desirable to have all portions of the circuit of the transmitter and receiver employed in such equipment accessible for servicing on short notice. At the same time, it is known that such equipment normally is quite bulky and cumbersome, including usually one or more cathode ray tubes used for locating an object in space. For effective operation, it is desirable that all controls be as accessible as possible so that ordinarily a control panel is required to which are brought all the necessary conductors and on which are located the necessary meters and cathode ray tubes. It is desirable to have the circuits enclosed and safeguarded to as great an extent as possible, since relatively high potentials are employed for the circuits of the equipment. Accordingly, it is a primary object of my invention to provide a new and improved cabinet construction for high frequency equipment in which the circuits of the cabinet are normally enclosed and which permits easy withdrawal of the circuits and components for inspection and servicing.

It is still another object of my invention to provide a new and improved chassis construction for radio equipment which is normally contained in an enclosure and which may be withdrawn from that enclosure and rotated to provide access to circuits and equipment located on such a chassis.

It is a further object of my invention to provide a new and improved telescoping means for rotatably supporting an object.

It is a still further object of my invention to provide a new and improved cabinet construction for slidably supporting an object which is inexpensive and simple in construction.

One of the features of my invention consists in rotatably supporting an object upon a slide constructed of a plurality of telescoping channel members. The telescoping slide is provided with a plurality of locks to control both longitudinal and rotational positioning of the supported object relative to the channel members.

The features of my invention which I believe to be novel are set forth with particularity in the appended claim. My invention itself, however, both as to its organization and method of operation, together with further objects and advan-

2

tages thereof, may best be understood by reference to the following description taken in connection with the accompanying drawing. In the drawing, Fig. 1 represents a cabinet construction for high frequency apparatus showing a chassis in a withdrawn and rotated position; Figs. 2-4 are side elevation views showing three positions of the rotating support and interlocking structure of the cabinet of Fig. 1; Fig. 5 is a cross-sectional view of Fig. 4 taken along the line 5—5; Figs. 6 and 7 are views of a portion of the telescoping slide of the cabinet of Fig. 1 which illustrate certain operational features thereof; and Fig. 8 is a cross-sectional view of the structure of Fig. 6 taken along the line 8—8.

Referring to Fig. 1, I have there shown an equipment for locating objects in space by means of radio waves which includes an enclosing metallic cabinet 1 divided into an upper portion 2 and a lower portion 3. In the upper portion 2 there is contained a chassis 4 having a front wall or control panel 5 on which are located a plurality of control knobs 6—11 and three cathode ray tubes 12—14. Likewise, there are provided on the front panel 5 a plurality of hinge covers 15 which provide easy access to additional controls located behind panel 5. The chassis 4 includes the usual circuit wiring, condensers, and resistors (not shown) employed in radio transmitting and receiving apparatus of this type. The lower portion 3 of the cabinet is adapted to contain four sliding chassis (not rotatable) for power supplies and other circuit elements. On the front of one of the four panels 3 which cover the lower portion 3, there is provided a plurality of telephone hand sets 16.

Since, in the use of such equipment, it is often desired to have ready access to the chassis and the wiring thereon, I provide a slidable support for the chassis 4 which comprises, on each side of the chassis, a set of three telescoping sliders or channel members 17—19. Outer channel 17 and intermediate channel 18 are standard in form, while inner channel 19 has a re-entrant central portion. Channel 17 is welded or otherwise secured to the inner surface of the side wall of cabinet 1. Both channels 17 and 18 are provided, respectively, at their ends extending toward the front of the cabinet with straps 20, 21 attached to the outer surface of the web and extending around the flange thereof. Furthermore, for reasons to be pointed out later, the portions of the upper flanges of channels 17, 18 adjacent the straps 20, 21 are cut away.

55 I provide means for supporting chassis 4 for

rotation with respect to the supporting channel structure when the chassis is withdrawn from the cabinet 1. This supporting means comprises a steel pin or shaft 22 which is secured to a side wall 23 attached to the chassis and which is journaled in a hole provided in the re-entrant central portion of channel 19. The shafts 22 on opposite sides of the chassis are located substantially at the center of gravity of the chassis so that the chassis may be rotated relatively easily about the axis of these shafts. In order that the position of the chassis may be fixed at various points in its rotation, I provide a plate 24 which is welded to the inner surface of the channel 19. Secured to the outer surface of the plate 24, as by welding, are three U-shaped metallic members 25. Members 25, one of which is shown in enlarged view in Fig. 5, are provided with aligned apertures in their two legs through which passes a pin 26 on which is secured a disk 27. A spring 28 surrounds the pin 26 between the two legs of the member 25. The pin 26 is biased upwardly through the upper of the apertures in the member 25 by means of the spring so that it extends radially outwardly from the plate 24. The assembly of the elements 25-28 forms one portion of a structure for locking the chassis in a rotated position. The other portion of the locking structure comprises a U-shaped member 29 having its web secured to the side wall 23. The legs of the U-shaped member 29 are provided with aligned apertures between which is located a guide tube 30. Positioned within the guide tube 30 is a pin 31 having attached thereto a disk 32 adapted to engage the inner surface of the front panel 5. A spring 33 is adapted to be compressed between the disk 32 and the leg of the U-shaped member 29 adjacent the front panel. The pin 31 has a portion which extends, through the action of the spring 33, through the front panel and is accessible at the front of the panel 5.

In operation of the locking structure, as the chassis 4 is rotated on the shaft 22, one of the pins 26 is adapted to be depressed by a bevelled edge 34 of member 29. As the member 29 passes over the pin 26 and the apertures in the U-shaped members 25, 29 come into alignment, one of the pins 26, through the action of the spring 28, is forced into the tube 30 locking the chassis in position. In order to unlock the chassis from this position, the pin 31 is depressed by the operator's finger to move the pin 26 to a position to disengage it from the U-shaped member 29.

Preferably, three of the members 25 are provided so that the chassis normally is locked in a horizontal position, but may be rotated 30° counterclockwise or 90° clockwise. In the counterclockwise position, access is provided to tubes and other equipment on the upper surface of the chassis, while in the position of clockwise rotation, access is provided for servicing of all wiring and components on the under side of the chassis. These positions of rotation of the chassis are better evident from an inspection of Figs. 2-4. Fig. 2 shows the chassis when it is rotated 30° counterclockwise, in which position access is provided to the upper surface of the chassis and the components mounted thereon. In this position, the lowermost of the members 25 is aligned with the member 29 and the chassis is locked in this rotated position. In Fig. 3, there is shown the normal horizontal position of the chassis. In this position, the central of the members 25 is locked to the member 29. In Fig. 4 the chassis is shown rotated clockwise through

an angle of 90°. In this position, it is evident that the bottom surface of the chassis is available for inspection and servicing and in this position, the upper of the members 25 is locked to the member 29. Of course, in Fig. 1, the chassis is shown in a position intermediate the horizontal position and the 90° clockwise rotation.

In order to safeguard the operator in withdrawing the chassis from the cabinet 1, especially in rough weather on mobile installations, I provide means for limiting the outward motion of the chassis. Thus, referring to Figs. 6-8 jointly, I have shown enlarged views of a portion of the channel structure which illustrate locking means provided to limit the outward motion of the channel 19 relative to the channel 18. As previously pointed out, a strap 21 is secured to the channel 18 at its outermost end. The strap 21 is adapted to extend below the lower flange of channel 18 by a distance sufficient to accommodate a spring 35. The spring 35 surrounds a pin 36 and engages a disk 37 attached to the pin. The pin 36 is adapted to pass through a hole provided in the lower flange of channel 18 and engage a notch provided in the lower flange of channel 19. A similar notch 39 is provided in the upper flange of channel 19 opposite the notch 38. The upper flange of strap 21 is spaced from the upper flange of channel 19 to permit a limited amount of vertical motion of the channel 19 relative to channel 18. Thus, in the operation of the telescoping support, the chassis 4 is withdrawn from the cabinet simply by pulling outwardly on handles 40 provided on the outer surface of the front panel. After a predetermined amount of horizontal movement, approximately half of the total movement, the notch 38 passes over the pin 36 and spring 35 moves the pin into the notch, preventing any further longitudinal movement of the channel 19 relative to the channel 18. A limited amount of vertical motion is permitted simply by lifting the front of chassis upwardly to tilt the channel 19 to the position shown by the broken line 19' in Fig. 6 or in full line in Fig. 7. Thus, when it is desired to replace the chassis, the operator simply lifts upwardly on the handles 40 pivoting the rear end of channel 19 on the bottom flange of channel 18 in an amount sufficient to allow the lower flange of channel 19 adjacent the notch to rise above the pin 36. This is best shown in Fig. 7 where, while tilting the channel 19 upwardly, a slight predetermined rearward push has been given to the chassis so that the front edge of the notch in the lower flange overhangs pin 36. When the chassis is now lowered, pin 36 is depressed and the chassis may be returned to the cabinet 1 by pushing on handles 40.

In order that the previously described upward tilting of channel 19 relative to channel 18 does not permit the chassis to move forward, as from a slanting deck on shipboard, I provide means to prevent the rear edge 41 of notch 38 from depressing the pin 36 to allow any further forward motion of channel 19 relative to channel 18. This means comprises a screw or removable pin 42 extending through the upper flange of strap 21 in a position slightly eccentric to the pin 36 and notches 38, 39. Screw 42 is positioned slightly to the right of the center line of pin 36 and notches 38 and 39 and has a diameter smaller than that of the pin 36. Screw 42, furthermore, extends through the upper flange of strap 21 a sufficient distance that it normally just clears the rear edge

43 of notch 38 when the chassis is lifted upward. If an attempt is made to pull the chassis farther forward, screw 42 acts as a stop to prevent the rear edge 41 of notch 38 from overhanging the upper surface of pin 36. Screw 42 is sufficiently eccentric to the pin 36 that, when the rear edge 43 engages the right-hand edge of the screw 42, as shown by broken line 19 in Fig. 6, the rear edge 41 of slot 38 in lower flange of channel 19 does not overlie pin 36. As a result, the only way in which channel 19 may be completely withdrawn from channel 18 is by removing screw 42 to eliminate the protective feature described. The previously described tilting movement of channel 19 with respect to channel 18 is permitted by the cutaway portion 44 in the upper flange of channel 18, the longitudinal extent of the cutaway portion 44 being sufficient to allow the lower flange of channel 19 to clear the pin 36.

Fig. 8 is a cross-sectional view of the channel support taken along the line 8—8 of Fig. 6 and shows the position of screw 42 relative to pin 36. It shows likewise how the pin 36 is received into the notch 38 in the lower flange of channel 19, being pressed upwardly by spring 35.

Strap 20, which extends around the outer end of channel 17, is constructed similar to strap 21 and is likewise provided both with a pin similar to pin 36 and a screw similar to screw 42. Thus, the same motions of slider or channel 18 relative to slider or channel 17 are permitted when the channels are locked in position after a predetermined forward motion of channel 18 relative to channel 17. Channel 18 can be released only by lifting the chassis slightly and pushing rearward on handles 40, to position the front edge of the notch in the lower flange of channel 18 over the spring operated pin which is supported by strap 20 and which passes through the lower flange in channel 17. Both notches in channels 18 and 19 usually clear both pins simultaneously when the chassis is lifted and pushed inwardly.

An important advantage of my invention is that it permits servicing to be performed either on the underside or top of a chassis quickly and easily. The chassis is pulled out from the cabinet simply by an outward force on the handles 40. Preferably, the sliders or channels 17—19 are merely sufficiently lubricated that free sliding action is obtained. However, the downward force on the channels is sufficient to retain them in any withdrawn position. After the chassis has been withdrawn a certain amount, one or the other of the pairs of channels 17, 18 or 18, 19 will be locked together by one of the spring operated pins 36 engaging the associated notch 38. Thereafter, further outward movement is permitted until the other of the spring operated pins 36 engages its associated notch 38.

In its outward position, the chassis may be rotated either up or down on the pivots 22 which are located near the center of gravity of the chassis 4. The chassis, due to its weight, remains at any angular position and may be locked in either a vertical position, a horizontal position, or a position 30° below horizontal. The push button or pin 31 on the front panel unlocks the chassis for rotating motion. The chassis is held

in its withdrawn position by means of the spring operated pins 36. These pins are released only by lifting the chassis slightly to tilt upwardly either the channel 19 relative to the channel 18 or channel 18 relative to channel 17 or both a sufficient amount to permit the front edge of the respective notch 38 to engage the upper end of the respective pin 36. Thereafter, the chassis may be pushed inwardly until either the strap 21 engages the strap 20 or the central of the U-shaped members 25 engages strap 21. At this position, the other of the spring operated pins 36 prevents any further rearward motion of the chassis until the chassis is again lifted slightly to clear this other pin. Thereafter, the chassis may be moved to a completely closed position within cabinet 1.

Another important advantage of my construction is that it provides safety to the operator in that the chassis cannot be withdrawn or forced by inertia, as during a sharp turn, beyond the ends of the sliders 17—19 without intentionally loosening of the screws 42.

While I have shown a particular embodiment of my invention, it will of course be understood that I do not wish to be limited thereto since various modifications may be made, and I contemplate by the appended claim to cover any such modifications as fall within the true spirit and scope of my invention.

What I claim as new and desire to secure by Letters Patent of the United States is:

In a cabinet structure, the combination of a pair of parallel walls, a pair of telescoping slides supported respectively on opposing surfaces of said walls, an object to be supported pivotally mounted on said slides, one of said slides having a plate affixed thereto, a plurality of resiliently biased pins supported on said plate at points spaced along the edge thereof, an arm having an aperture therein secured to said object and adapted to receive said pins as said object is rotated relative to said slides to lock said object into position determined by said pins, and means whereby said pins may be removed from said aperture to permit rotation of said object relative to said slides.

DONALD B. KEIM.
